(57) **CLAIM**

The ornamental design for a computer generated image for a display panel or screen, as shown and described.

DESCRIPTION

FIG. 1 is a front elevational view of a first embodiment of a computer generated image for a display panel or screen showing our new design;

FIG. 2 is a front elevational view of a second image of FIG. 1;

FIG. 3 is an enlarged front elevational view taken along the lines 3—3 of FIG. 2;

FIG. 4 is a front elevational view of a second embodiment of a computer generated image for a display panel or screen showing our new design;

FIG. 5 is a front elevational view of a second image of FIG. 4; and,

FIG. 6 is an enlarged front elevational view taken along the lines 6—6 of FIG. 5.

The broken lines illustrate portions of the computer generated image that form no part of the claimed design.
